UNITED STATES PATENT OFFICE.

JAMES R. GOODWIN, OF EVANSVILLE, INDIANA, ASSIGNOR TO THE STEEL SCAFFOLDING CO., OF EVANSVILLE, INDIANA, A CORPORATION OF INDIANA.

ADJUSTABLE LADDER JACK.

Application filed April 6, 1922. Serial No. 550,125.

To all whom it may concern:

Be it known that I, JAMES R. GOODWIN, a citizen of the United States, residing at Evansville in the county of Vanderburgh 5 and State of Indiana, have invented certain new and useful Improvements in Adjustable Ladder Jacks, of which the following is a specification.

This invention relates to an improved adjustable bracket or "jack" adapted to be attached to a ladder to serve as a support for a plank or platform.

Ladder brackets or jacks are used by painters, carpenters, and others for both 15 interior and exterior work on buildings, it being a usual practice to employ two or more ladders, each carrying a bracket or jack and to support a plank or platform by the brackets or jacks.

20 My invention relates to that general class of ladder jack having legs provided with hooks adapted to suspend the device from a rung of the ladder in such manner that the legs rest against other rungs thereof, 25 there being provided two bearing bars, one pivoted to the legs and adapted to support the plank, the other bearing bar serving as a brace or support having an adjustable connection to the legs.

30 In this type of ladder jack I have made certain improvements which appear more fully hereinafter and which are shown in the accompanying drawing as also being recited in the claims. The improvements simplify, strengthen, and render safe the jack.

35 Among the improvements embodied in my invention are the construction and form of the legs, the use of a ratchet plate located between the legs and riveted to them which 40 not only reinforces the legs but insures against accidental detachment of the brace or lower bearing member; the construction of the lower end of the brace or lower bearing member and the manner in which it 45 cooperates with the legs and the ratchet plate to effect a positive lock which cannot become accidentally disengaged; an improved cross brace for the diverging upper parts of the legs, and the construction of 50 the inner end of the upper bearing member and its manner of pivotal connection to the cross brace aforesaid.

The legs are preferably of angle iron to increase their rigidity and strength; the

bearing members are of duplex construction 55 to render them rigid and capable of withstanding lateral springing or buckling; the legs are of such length that they bridge three rungs of the ladder and their divergent parts bridge two rungs of the ladder, 60 while their riveted parts which carry the ratchet plate are arranged to bridge two rungs of the ladder; consequently, tendency of the jack to wobble or swing laterally is minimized and the weight imposed upon 65 the lower bearing member or brace is distributed between two rungs of the ladder.

70 My jack, while providing for all adjustments desired or necessary to meet requirements of use on ladders arranged at different angles to the wall of the building, can be used in reverse position, that is, between the ladder and the building without changing the adjustment; hence, as the painter or carpenter works at lower levels he may simply remove the jack and dispose it on the inside of the ladder without readjusting it and then reset the plank on the upper bearing members of the jacks used. The lower bearing member being completely detachable from the ratchet plate, the jack can be folded into flat condition when it is desired 75 to transport it from place to place or to arrange it in compact form. By reason of the improved construction entering into the 80 jack, special screws, stays, bolts, nuts, etc., which have been commonly employed in ladder jacks, are entirely dispensed with and there are no loose parts which have to be tightened to render the device effective or 85 which will be liable to accidental detachment to the danger of the user, or become lost, as rivets are used exclusively in my 90 jack.

95 In the accompanying drawings:

Figure 1 is a perspective view showing the jack applied to the outer side of a ladder, dotted lines representing the plank which may be supported thereby;

Fig. 2 is a side elevation showing the jack 100 in use on the inner side of the ladder, between the ladder and the building, the rungs of the ladder being shown in section; and Fig. 3 is a detail perspective of the locking end of the lower bearing member, legs, and 105 ratchet plate.

The legs 1 which are preferably of angle iron for the purpose of rigidity and

strength, are of substantial Y-shape, the upper parts thereof diverging for a distance preferably sufficient to cause them to bridge two of the rungs of the ladder 2, of which 5 a portion is shown. The legs terminate at their upper ends in hooks 3 which are adapted to hook over a rung of the ladder. The divergence of the upper parts of the legs 1 is such that the hooks 3 are located well to 10 wards the stiles of the ladder and consequently the gripping points of the jack are so separated that tendency to tilt or wobble is minimized. The divergent parts of the legs 1 are connected by a cross brace 4 of 15 strap metal which is riveted to them at its ends as shown at 5. The cross brace 4 insures rigidity of the divergent part of the legs in relation to each other. This cross brace is provided with struck-up or bent ears 20 6 and in order not to weaken the cross brace, these ears are formed on the upper part of the cross brace which is, therefore, wider at its center than at its ends.

The lower part of the legs 1 extend in the 25 form of a stem, parallel to each other, for a distance adapting them to bridge two of the rungs of the ladder. Interposed between the straight parts of the legs 1 is a ratchet plate 7 which is of stiff sheet metal to insure 30 rigidity and strength. Rivets 8 permanently fasten the ratchet plate 7 to, and between, the straight portions of the legs 1 and rigidly connect the said straight portions together. The location of the ratchet plate 7 35 between the straight parts of the legs 1 and riveting it to the legs, strongly reinforces the stem of the legs so that there is no possibility of buckling and, beside that, no possibility of accidental detachment of the 40 ratchet plate or of its becoming bent. This is of importance because the safety of a jack of this class is no greater than the safety of the adjustable connection between the supporting members and the leg. Furthermore, 45 it will be seen that the ratchet plate 7 is disposed between two of the rungs of the ladder so that the weight of the stem and the ratchet plate have to support, is distributed between two rungs of the ladder. The 50 ratchet plate 7 is provided with relatively long or deep notches 9 which extend parallel, or substantially so, to the stem of the leg and the mouths 10 are at an abrupt angle to the length of the notches 9. In consequence, 55 the hooks 11 are long and substantially parallel to the length of the stem of the legs. This construction insures against accidental detachment of the lower bearing bar or brace which is shown at 12 and has a 60 decided advantage over lateral opening or merely inclined slots.

The upper bearing bar 13 and the lower bearing bar or brace 12 are both of duplex construction, being made of steel bars riveted together at 14, thus insuring against 65

lateral spring or buckling. The upper bearing bar 13 is provided with divergent extremities 15 at its inner end, these being pivoted on a long rivet pin or bolt 16 whose ends are riveted down on the ears 6. The 70 extremities 15 lie inside the ears 6 and close to them so that the possibility of spreading is prevented and the double pivot thus provided minimizes any twisting or torsional action of the bearing bar 13. 75

The outer end of the bearing bar 13 is spread as at 17 and receives the hook-shaped welded end 18 of the lower bearing bar 12 which is pivoted thereto on a rivet 19. The hooked-shaped end 18 engages the plank 20 shown in dotted lines, and prevents it from slipping off of the bearing bar 13 when the jack is in the position shown in Figure 1.

The lower end of the lower bearing bar 12 is spread apart as shown at 21 so as to 85 straddle not only the ratchet plate 7 but also the parallel webs of the stem of the legs. This overlapping of the legs by the ends 21 prevents any possibility of displacement of the bearing bar 12. A bolt 22 extends from 90 one part to the other of the fork or end 21 and is riveted or headed down against the outer faces of the members of said fork so that there is no possibility of detachment. This bolt 22 is of a size adapting it to easily 95 yet snugly enter the mouths 10 and to fit snugly and easily in the slots 9.

In Figure 1 I have shown the manner in which the jack is used on the outer face of a ladder as, might be the case, when the 100 painter or carpenter is supported by the upper part of the ladder and as far down thereon as he can conveniently reach the wall of the building.

In Figure 2 the jack is shown on the inside of the ladder, that is, between the ladder and the wall of the building as would be necessary when working on lower parts of the wall in order to permit the painter or carpenter to easily reach the wall. The 110 construction of my jack enables it to be removed and re-hung in its reversed position, as shown in Figure 2, without the necessity of readjusting the lower bearing bar 12. In that connection, it will be observed that the 115 depths and arrangement of the slots 9 and their mouths 10, render it impossible for the bolt 22 to become accidentally disengaged from the ratchet bar 7.

What I claim is:

1. A ladder jack comprising a double leg whose upper parts are arranged in spaced relationship and are provided with hooks to engage a rung of a ladder and whose lower parts extend closely parallel in the form of a stem, a ratchet plate located between, and secured to the said lower parts and forming a part of the stem aforesaid, an upper bearing bar pivoted to the upper parts of the leg, and a lower bearing bar pivoted 125 130

to the upper bearing bar and having means for engaging the teeth of the ratchet plate.

2. A ladder jack comprising a double leg whose upper parts are arranged in spaced 5 relationship and are provided with hooks to engage a rung of the ladder and whose lower parts extend closely parallel in the form of a stem, a ratchet plate located between, and secured to, the said lower parts and 10 forming a part of the stem aforesaid, a cross brace connecting the upper parts of the leg, an upper bearing bar having parts arranged in spaced relationship to each other which are pivoted to the cross brace, 15 and a lower bearing bar pivoted to the upper bearing bar and having a forked shaped end provided with a bolt for engaging the teeth of the ratchet plate.

3. A ladder jack comprising a double leg 20 whose upper parts diverge and are provided with hooks to engage a rung of a ladder and whose lower parts extend parallel in the form of a stem, a ratchet plate located between, and secured to the members of the 25 stem aforesaid, a cross brace connecting the divergent upper parts of the leg, said cross brace having separated lugs or ears, an upper bearing bar provided with divergent parts at its inner end which are pivotally 30 connected to the lugs or ears and a lower bearing bar pivoted to the upper bearing bar and having means for engaging the ratchet plate.

4. A ladder jack comprising a double leg 35 whose upper part has divergent sections provided with hooks to engage a rung of a ladder and whose lower part has parallel sections secured together, a cross brace connecting the divergent upper parts of the leg 40 together, said cross brace being provided with separated ears, an upper bearing bar having divergent members at its inner end which are pivoted to the ears aforesaid, and a lower bearing member pivoted to the up-

per bearing member and provided with 45 means for effecting locked engagement with the stem of the legs.

5. A ladder jack comprising a double leg 50 the members of which diverge at their upper parts and are provided with hooks for engaging a rung of a ladder and whose lower parts extend parallel in the form of a stem, a ratchet plate located between the members 55 of said stem and secured to them, a cross brace connecting the divergent upper parts of the leg together, said cross brace being provided with separated lugs which are bent up therefrom, an upper duplex bearing bar composed of members secured together which diverge at their inner ends and are 60 disposed adjacent the lugs of the cross brace, a pivot bolt connecting said divergent ends to the lugs, the outer end of the upper bearing bar having its parts spread, a lower duplex bearing bar having one end received 65 between and pivoted to said spread ends of the upper bearing bar and extending thereabove to serve as a plank retainer, the other end of the lower bearing bar being spread and provided with a cross pin or bolt adapted 70 to engage the teeth of the ratchet plate, said lower end of the lower bearing bar straddling the stem of the leg.

6. A ladder jack having a leg provided 75 with means for its attachment to a ladder and provided with a stem comprising closely related parallel parts, a ratchet plate located 80 between and connected to the stem and forming a part of said stem, said ratchet plate having slots extending substantially parallel to the stem and provided with entrance mouths disposed at an abrupt angle to said slots, an upper bearing bar pivoted to the leg, and a lower bearing bar connected to the 85 upper bearing bar and provided with means to enter the slots aforesaid.

In testimony whereof I affix my signature.

JAMES R. GOODWIN.
